UNITED STATES PATENT OFFICE.

LINDSAY MURDOCH, OF WASHINGTON, DISTRICT OF COLUMBIA.

CARRYING ATTACHMENT FOR BICYCLES.

SPECIFICATION forming part of Letters Patent No. 733,865, dated July 14, 1903.

Application filed March 27, 1903. Serial No. 149,851. (No model.)

To all whom it may concern:

Be it known that I, LINDSAY MURDOCH, a citizen of the United States, residing at 811 Sixth street, northwest, Washington, District 5 of Columbia, have invented certain new and useful Improvements in Carrying Attachments for Bicycles, of which the following is a specification.

My invention is an improved carrying attachment for bicycles for carrying an umbrella, luggage, and baby-seat, or any of said devices; and the invention consists in certain novel constructions and combinations of parts, as will be hereinafter described and 15 claimed.

In the drawings, Figure 1 is a side elevation of the apparatus as in use, parts being broken away. Fig. 2 is a detail view showing the main support formed integrally with 20 the frame of a bicycle. Fig. 2^a illustrates a construction of main support adapted for connection with bicycles already in use. Fig. 3 is a detail side elevation of the umbrella and frame, showing the latter with the rearward extension. Fig. 4 is a detail perspective view of the bracket. Fig. 5 is a detail perspective view of the rack for supporting the baby-seat or other object which it may be desired to carry. Fig. 5^a is a detail perspective view of the upper side of the platform. Fig. 6 is a detail perspective view of the box-like receptacle. Fig. 6^a is a detail elevation of a portion of the rear side of the box-like receptacle.

35 In carrying out my invention I provide means for supporting several devices from the frame of a bicycle. This includes a main support held to the bicycle-frame. In Fig. 2 I show such support cast integrally with the 40 frame of a bicycle and provided with the post b, having in its upper side a socket c to receive the staff of the umbrella. This may be desirable in the manufacture of new machines; but in order to permit the convenient 45 application of my invention to machines already in use I may prefer the construction shown in Fig. 2^a, in which the main support a is in the form of a clasp adapted to fit over and around the front portion of the frame of 50 a bicycle and be secured by bolting at g, as will be understood from Fig. 2^a. In the construction shown in Fig. 1 the main support

comprises the opposite side wings f and the upper longitudinal tubular portion e, provided with an opening e' to receive the upper 55 extension of the front tube of the framing, the side wings f being provided with semi-circular or rounded portions d to fit around said post, said rounded portions d being practically in alinement with the opening e', as 60 shown in Fig. 2^a. The post b, as shown in Figs. 2 and 2^a, is made square or non-circular to receive the boxing at the rear end of the main bracket. (Shown in Fig. 4.) The umbrella has its handle h formed to fit in the 65 socket c and its frame composed of the ribs j and i, the ribs i extending to the rear and being longer than the ribs j, so the umbrella will form a canopy covering the person of the 70 rider.

The main bracket is shown in Fig. 4 and is provided at its rear end with a boxing k, having an opening l to fit on the post of the main support and is provided at its front end with a head A, having the opposite upright grooves 75 t and flanges u to fit corresponding portions in the box-like receptacle, as will be presently described. This main bracket has the upwardly-inclined rear arm m and the horizontal front arm extending from the forward 80 end of the inclined arm to the head A, bracing-ribs q being provided at the juncture of the front and rear arms with the bracket and extending from the upper to the lower edges of the bracket, at the middle thereof, as shown 85 in Fig. 4, the lower inclined edge of the rear arm of the bracket extending at o to the lower end of the rib r, as shown in Fig. 4. The rib r serves as a stop to prevent any backward movement of the platform B when the latter 90 is fitted by means of its carrier b' on the front arm of the bracket, as shown in Fig. 1. The bracket-carrier has the depending lugs a, which straddle the arm of the bracket, fitting over the same, as shown in Fig. 1, and being 95 held from rearward movement by the ribs r and against forward movement by engagement with the head A at the front end of the bracket. The bed or rack B rests on the carrier a' and may support the chair D, as shown 100 in Fig. 1. In thus supporting the chair its supporting-springs D' may fit in the sockets b' of the rack or base B, as will be understood from Figs. 1 and 5^a of the drawings.

By the described construction the bed or rack may be readily applied to or removed from the bracket whenever desired, and the chair can be conveniently connected with the rack or base and removed at pleasure.

- 5 The base or rack B is provided at its front end near its opposite sides with openings c', which receive pins e' on the rear side of the box or receptacle in order to steady the rack 10 and receptacle in place by interlocking the receptacle and the rack, as will be understood from Figs. 1, 5^a, and 6^a of the drawings. The box-like receptacle F is provided with openings f' for straps to secure any articles 15 within the box or receptacle and is provided with the opening d' in its rear side for the admission of the front flanges of the head A to permit said head to interlock with the rear side of the receptacle F in order to properly 20 carry the latter at the front end of the bracket. By the described construction it will be noticed the inclination of the main bracket is such as to support the receptacle F and the platform above the front wheel of the bicycle 25 and out of the way and that the receptacle may be used in connection with the chair and the umbrella, and the umbrella will be so supported as to shield the occupant of the chair as well as the rider of the bicycle, the several 30 parts being conveniently removable and the attachment being so constructed as to permit its convenient application to and removal from a bicycle whenever desired.

Having thus described my invention, what 35 I claim as new, and desire to secure by Letters Patent, is—

1. A carrying attachment for bicycles comprising the main support having an upright post and a socket for an umbrella-staff, the 40 main bracket provided at its rear end with a socket to fit on the upright post of the main support, and at its front end with a head for interlocking with the box-like receptacle and in rear of said head with a horizontal arm 45 and with stop devices at the rear end of said arm, the base or rack, the carrier therefor having depending lugs straddling the horizontal portion of the bracket between the front head of said bracket and the stops of 50 the rear end of said horizontal portion, and the box-like receptacle interlocked with and carried by the front head of the bracket, substantially as set forth.

2. The combination in a carrying attachment for bicycles, of the main bracket, means 55 whereby said main bracket may be carried from the frame of the machine, a box-like receptacle at the front end of said bracket, and a platform supported by the bracket in rear of the box-like receptacle and adapted for use substantially as set forth.

3. A carrying attachment for bicycles comprising a main bracket, a box-like receptacle carried by the main bracket, and a platform 65 also carried by the bracket, substantially as set forth.

4. The combination in a carrying attach-

ment for bicycles, of a main support, a bracket carried by said main support, and detachably connected therewith at its rear 70 end, a box-like receptacle detachably connected with the front end of the bracket, and the platform detachably connected with the bracket in rear of the box-like receptacle, substantially as set forth.

5. The combination in a carrying attachment for bicycles, of the main bracket, the platform and a carrier therefor, having depending lugs straddling the main bracket, substantially as set forth.

6. A carrying attachment for bicycles, comprising a main support provided with means for supporting an umbrella, a main bracket connected with said main support, and carrying devices supported on the main bracket, substantially as set forth.

7. A carrying attachment for bicycles comprising a main support provided with means for holding an umbrella, a main bracket detachably connected with said main support, 90 and carrying devices detachably connected with the main bracket substantially as set forth.

8. The combination in a carrying attachment for bicycles, of the main bracket provided at its front end with the head having the opposite upright grooves, and the box-like receptacle interlocking with said head for supporting the receptacle at the front end of the bracket, substantially as set forth.

9. A carrying attachment for bicycles comprising a main bracket, a box-like receptacle detachably connected with the front end of the main bracket, the platform and the carrier therefor, having depending lugs arranged 105 to straddle the main bracket, in rear of the connection of the box-like receptacle therewith, substantially as set forth.

10. A carrying attachment for bicycles comprising a main bracket having an upwardly-inclined arm, and a horizontal arm projecting from the front end of the upwardly-inclined arm, and a platform supported on the horizontal arm of the bracket, substantially as set forth.

11. A carrying attachment for bicycles comprising a main support having an upright provided in its upper end with a socket for the umbrella-handle, a bracket having a socket fitting over said upright, and carrying devices on the bracket, substantially as set forth.

12. In a carrying attachment for bicycles, a main support, comprising a clasp to fit over and be secured to the frame of a bicycle and having the opposite wings or jaws curved to 125 fit the frame of the bicycle, the bracket detachably connected with said main support and the carrying devices on the bracket, substantially as described.

13. A carrying attachment for bicycles provided with a main support consisting of the opposite wings or plates having outwardly-rounded portions to fit the upright tube of a bicycle-frame, and a horizontal tubular por-

tion at the upper end of the support and having, in line with said rounded projecting portions of the said plates, an opening to encircle the upper extension of the front tube of the bicycle, substantially as set forth.

5 14. A carrying attachment for bicycles comprising the main bracket, the platform, the carrier therefor detachably connected with the bracket, and the chair detachably con-

nected with the platform, substantially as set forth.

In testimony whereof I affix my signature in presence of two witnesses.
